INVENTOR

BY *Victor J. Evans*

ATTORNEY

W. L. Coomer

WITNESS:

UNITED STATES PATENT OFFICE.

CHARLES E. AMES, OF MILLSAP, TEXAS.

CLOTHESLINE.

Application filed November 10, 1922. Serial No. 600,124.

To all whom it may concern:

Be it known that I, CHARLES E. AMES, a citizen of the United States, residing at Millsap, in the county of Parker and State 5 of Texas, have invented new and useful Improvements in Clotheslines, of which the following is a specification.

This invention relates to clothes lines, particularly to those of the metallic type, and 10 has for its object the provision of a clothes line formed of a series of similar links connected together or interposed in a flexible connector and so constructed as to provide clothes holding means without the employment 15 of any clothes pins or the like.

An additional object is the provision of a line of this character which will be simple and inexpensive in manufacture, highly efficient in use, durable in service and a general 20 improvement in the art.

With the above and other objects and advantages in view the invention consists in the details of construction to be hereinafter more fully described and claimed and illustrated in the accompanying drawings, in 25 which:

Figure 1 is a side elevation of a line constructed in accordance with my invention.

Figure 2 is a cross section on the line 2—2 30 of Figure 1.

Referring more particularly to the drawings I have shown the line as consisting of any desired number of links 10 each of which is formed from a single length of 35 resilient wire bent upon itself at points spaced from the ends to define an elongated straight stretch 11, these bends being twisted as indicated at 12 to provide terminal eyes 13 which may be interengaged 40 or which may be connected by auxiliary links or flexible members of any type preferred. Inwardly of the eyes 13, portions of the wire extend in parallel contiguous relation to the stretch 11 to define clamps 14 and 45 each clamp portion 14 is formed with a coil 15 which will provide resilience. Inwardly of the coils 15, the end portions of the wire are bent at an acute angle to the stretch 11 and toward each other, as illustrated at 16. 50 From the inner ends of the angular portions 16 the end portions of the wire extend at right angles to the stretch 11 and in contacting relation, as at 17, with the terminals 55 coiled about the center of the stretch 11, as shown at 18.

The line is constructed of any desired number of these links connected in any preferred manner and the portions co-operating with the stretch 11 constitute clamps for holding the clothes to be dried without any 60 necessity whatever for the employment of clothes pins or other auxiliary securing means. The end portions 17 operate as clamping means for holding garments or articles between them. 65

From the foregoing description and a study of the drawings it will be apparent that I have thus provided a simply constructed and consequently very inexpensive clothes line which is entirely metallic and 70 which will therefore have the maximum durability in addition to its ordinary function as brought out above.

While I have shown and described the preferred embodiment of the invention it is 75 of course to be understood that I reserve the right to make such changes in the form, construction and arrangement of parts as will not depart from the spirit of the invention or the scope of the subjoined claims. 80

Having thus described my invention I claim:

1. A clothes line comprising a series of similar links connected together and each formed from a single length of resilient wire 85 including an elongated straight stretch twisted to define eyes and clamping portions lying against the straight stretch adjacent the eyes, the wire having its end portions extending toward each other from said clamping portions and at an acute angle with respect to the elongated straight stretch with the ends coiled about the central portion of the elongated straight stretch. 90

2. A clothes line comprising a plurality of connected similar links, each formed from a single length of wire including an elongated straight stretch twisted to define eyes and clamping portions thereadjacent arranged in contacting relation to the straight stretch, the wire being coiled at the inner ends of 100 said clamping portions and extended at an angle to the straight stretch, the inner ends of said angular portions being extended at right angles to the straight stretch and in contacting relation to each other with the terminals coiled about the center of the straight stretch. 105

In testimony whereof I affix my signature.
CHARLES E. AMES.
